UNITED STATES PATENT OFFICE.

WILLIAM E. PUTNAM, JR., OF BROOKLINE, MASSACHUSETTS.

FIRE-EXTINGUISHER.

1,098,837.

Specification of Letters Patent. Patented June 2, 1914.

Application filed July 22, 1912. Serial No. 710,831.

To all whom it may concern:

Be it known that I, WILLIAM E. PUTNAM, Jr., a citizen of the United States, and resident of Brookline, in the county of Norfolk and State of Massachusetts, have invented new and useful Improvements in Fire-Extinguishers, of which the following is a specification.

This invention relates to fire extinguishers of the sprinkler type adapted to be installed in buildings and automatically to discharge in the presence of heat.

The object of my invention is to provide a fire extinguisher of novel and improved construction which makes it possible to dispense with the present form of fire extinguisher systems, consisting of elaborate and costly systems of piping and sprinkler heads. Instead of using water, as is customary in extinguishing systems permanently installed in buildings, with my invention it is possible to use a chemical fire extinguishing fluid thus avoiding the danger of destroying or injuring the contents of the building by a flood of water, as frequently happens, causing more damage than the fire which is extinguished.

In the accompanying drawings which illustrate certain embodiments of my invention,—Figure 1 is a vertical central section showing a fire extinguisher containing my invention in one form; Fig. 2 is a similar sectional view of a fire extinguisher containing my invention in modified form.

Similar reference characters are employed in all the figures to indicate corresponding parts.

a represents a container casing, having an outlet *b*, normally sealed by a cap *c*; the container casing may be cylindrical in form or of other suitable shape. The casing is adapted to be secured to the ceiling *d*, or other suitable support, in a room, by means of fasteners engaging flanges *f* of the casing, or in any other convenient way. Opposite the outlet *b* is a cup *g* supported by a yoke *h* to cause the fire extinguishing fluid when expelled from the casing to spray or sprinkle as in an ordinary fire extinguisher sprinkler head. In Fig. 1 the cap *c* for sealing the outlet is held in place by a well known sprinkler head device, consisting of two levers *i* soldered together with a soft, readily fusible metal *j*, which constitutes a holder fusible in the presence of heat, and normally resisting the pres-

sure which tends to eject the extinguishing fluid, but which when fused permits such pressure to force the extinguishing fluid out through the outlet *b*, unsealing the cap *c*. 60

In the form of the invention illustrated in Fig. 1 the casing *a* is cylindrical and is divided into two chambers by the partition *m'*, which is fitted to slide in the interior of the casing *a* after the manner of 65 a plunger. In the lower chamber the fire extinguishing fluid *k* is contained, and in the upper chamber the spring *s* is held under compression between the slidable partition *m'* and the top wall of the casing. 70 The periphery of the slidable partition *m'* is sealed to the walls of the casing by means of a flexible and collapsible tube *n*, the upper end of which is secured to the edge of the partition *m'*, and the lower end of 75 which is sealed at the bottom of the casing *a*, by being clamped between the cylindrical walls and the flat bottom wall of the casing *a*. The pressure holder *j* normally resists the pressure of the spring *s*, and when said 80 holder fuses spring *s* is released to force the slidable partition *m'* downward expelling the extinguishing fluid *k* as already described.

In the form illustrated in Fig. 2 the cylindrical casing *a* is provided with a partition or plunger *m²* fitted to slide within casing *a*. In the chamber formed between plunger *m²* and the walls of the casing *a* is the fire extinguishing fluid *k*. 85 Above the plunger *m²* is a spring *s* held under compression between the plunger *m²* and the top of the casing. In this form the fusible pressure holder is shown as consisting of a wire link or tie *o* connecting the 90 plunger *m²* and the top of the casing, and normally restraining the pressure of the spring *s*. In this form as the pressure holder directly connects the stationary and moving parts, the sprinkler releasing device 100 *i*, *j*, is dispensed with, since there is normally no appreciable pressure within the chamber containing the extinguishing fluid, and the cap *c* may be of any suitable material such as a fiber disk sufficient to hold 105 the fire extinguishing fluid *k* under normal conditions, but readily forced out under the influence of spring pressure when released. The upper part of the casing is provided with large apertures *p*, so as to be 110 freely open to the atmosphere to insure that changes of temperature due to a fire in the

vicinity of the extinguisher will be immediately felt by the fusible pressure holder *o*. When the holder is fused the pressure of spring *s* is released, forcing the plunger 5 *m*² downward, opening the seal *c* and expelling the fire extinguishing fluid *k* in the manner already described. In an extinguisher according to Fig. 2, a seal of paraffin, or other suitable material may be 10 poured on the upper side of plunger *m*² to prevent possibility of leakage between the plunger and the walls of the casing until the fusible holder is broken. Such seal would readily give way when the spring actuates the plunger. 15

With my invention it will be seen that each fire extinguisher device is a unitary self-contained device, complete in itself; that such units may be installed in a building in whatever numbers, or at whatever places desired, to afford full protection in all parts of the building without necessitating the employment of elaborate systems of piping such as are used in water sprinkler 25 systems now in vogue. Furthermore, danger of water damage to the contents of the building is wholly eliminated by the use of the fire extinguishing chemical fluid, instead of water, and by the use of such fluid in 30 quantities so small that there is no possibility of flooding the building while the quantity of the fluid although insufficient to flood the building is sufficient, owing to its greater effectiveness as a fire extinguisher, to do the 35 work of a very much larger volume of water.

I claim:

1. A fire extinguisher, comprising a container casing, having a normally sealed outlet, a partition fitted to slide within said container casing, a fire extinguishing fluid within the chamber formed by said partition and the walls of the casing, a spring within said casing to exert pressure on said 40 slideable partition, a holder fusible in the presence of heat for restraining said spring pressure and adapted when fused to permit said pressure to force said partition inward, open said sealed outlet and expel said fluid. 45

50 2. A fire extinguisher, comprising a container casing having a normally sealed outlet, a partition fitted to slide within said container casing, a fire extinguishing fluid within the chamber formed by said parti-

tion and the walls of the casing, a spring 55 within said casing to exert pressure on said slideable partition, a holder fusible in the presence of heat connecting said slideable partition and the walls of said casing to restrain said spring pressure and adapted 60 when fused to release said spring and permit the same to force said partition inward, open said sealed outlet and expel said fluid.

3. A fire extinguisher, comprising a container casing having a normally sealed outlet, a partition fitted to slide within said container casing, dividing the casing into two chambers, one chamber being closed and containing a fire extinguishing fluid, and the other chamber being open to the 70 atmosphere, a spring in said open chamber exerting pressure on said slideable partition, and a holder fusible in the presence of heat within said open chamber for restraining said spring and adapted when fused to permit said spring to force said partition inward, open said sealed outlet and expel 75 said fluid.

4. A fire extinguisher, comprising a container casing having a normally sealed outlet, a plunger fitted to slide within said container casing forming with the walls of said casing a closed chamber, a spring to operate said plunger, and a holder connected to and supporting said plunger, fusible 85 in the presence of heat and accessible to the atmosphere, adapted normally to hold said spring in operative condition and when fused to permit said spring to force said plunger inward, open said sealed outlet and 90 expel said fluid.

5. A fire extinguisher comprising a receptacle having an extinguisher outlet passage, a sealing means for said passage, a plunger movable in said receptacle, a fusible 95 element, and spring means for actuating said plunger normally held in restraint but releasable upon fusion of said element whereby a pressure is created by the action of said plunger upon the extinguisher 100 chemical to forcibly render said sealing means inoperative.

Signed by me at Boston, Massachusetts, this eighteenth day of July 1912.

WILLIAM E. PUTNAM, JR.
